CLAIM

The ornamental design for a wireless handheld radio receiver, as shown and described.

DESCRIPTION

FIG. 1 is a perspective view of the wireless handheld radio receiver.

FIG. 2 is a front view of the wireless handheld radio receiver.

FIG. 3 is a back view of the wireless handheld radio receiver.

FIG. 4 is a right side view of the wireless handheld radio receiver.

FIG. 5 is a left side view of the wireless handheld radio receiver.

FIG. 6 is a top view of the wireless handheld radio receiver; and,

FIG. 7 is a bottom view of the wireless handheld radio receiver.

The broken line showing of environmental structures is for illustrative purposes only and forms no part of the claimed design.
